UNITED STATES PATENT OFFICE.

WILLIAM NORRIS, OF KENOSHA, WISCONSIN.

CROSSING GATE OR BARRIER.

Application filed March 26, 1926. Serial No. 97,683.

The object of this invention is to provide a barrier at the point where a highway crosses a railroad, the barrier being automatically controlled by an electric motor or 5 motors, the circuits of which are connected with the rails of individual and insulated blocks in the track.

A further object is to effect the result specified by employing a gate or barrier 10 movable into a chamber beneath the crossing when the track is clear, and movable upwardly to operative position when an approaching train has reached a predetermined position with reference to the crossing. 15

A further object is to provide controlling mechanism including a motor, cable winding means, and a gravity operated element, the position of the latter controlling the position 20 of clutches for placing the cable winding means in operative relation to the motor by which they are driven.

With the foregoing and other objects in view, the invention consists in the novel 25 construction and arrangement of elements described, illustrated and claimed, it being understood that modifications may be made within the scope of the claims without departing from the spirit of the invention.

30 In the drawings forming part of this application,

Figure 1 is a diagrammatic view of the circuits connected with the rails of the tracks, and connected with motors for the 35 cable winding means described below.

Figure 2 is a view in elevation and vertical section, the gate or barrier being shown below the crossing, and permitting traffic over the highway.

40 Figure 3 is a view similar to Figure 2, but showing the gate or barrier raised to operative position, in order to prevent vehicles from passing along the highway over the railway tracks.

45 Figure 4 is a detail view in section and elevation, showing a housing beneath the level of the roadway, into which the gate is movable, this housing being closed by a cover plate, pivoted at one side or edge portion, and automatically movable, incident to the movement of the operative elements, to the position of Figure 5.

50 Figure 5 is a view similar to Figure 4, showing the cover plate in open position.

55 The barrier comprises upper and lower cables 10 and 12, connected by vertical me-

tallic bars, such as 13, the end bars 13' having connection with springs, such as 14, and the latter having connection with vertically movable elements, or blocks 15 slidable on 60 vertical rods or guides 16. The barrier thus formed provides a shock absorbing structure, tending to avoid injury to a vehicle which may accidentally come into engagement therewith, it being understood that the 65 coiled springs 14 are of sufficient strength to obstruct the passing of the vehicle onto the tracks.

Beneath the level of the roadway is a 70 housing 18 adapted to receive the gate or barrier when the passage of vehicles over the railway tracks is to be permitted. This housing 18 is closed by a plate or cover designated 20, and hinged at 21, the plate being slotted as shown at 22, so that it will 75 clear the elements referred to below.

The blocks 15 have connected therewith 80 rack members 24 adapted to mesh with segmental racks 25 carried by the under side of cover plate 20, so that upon the upward movement of the gate, when tension is applied to the lifting cables, the racks 24 and 25 will engage and lift the plate or cover 20, and permit blocks 15 to move to the position of Figure 3. 85

The gate is elevated by means of cables 27 and 28, and is movable between posts 29 and 30, the latter being hollow for permitting the vertical movement of weight 31 in the box-like structure including the vertical walls of the member 30. 90

Cable 27 passes over a pulley 27' mounted in a bracket on post 29, and passes thence over a pulley 32 and downwardly to plate 33 with which it is connected, this plate having 95 connection by cable 34 with weight 31. Cable 28 passes over pulleys 32' and has connection with plate 33 at the point indicated, so that the position of weight 31 determines the position of the gate, and the weight is of sufficient size to raise the gate 100 when permitted to do so.

In order to elevate weight 31 and produce slack in cables 27 and 28, so that the gate may move downwardly, I provide a cable 35 passing over pulleys such as 36' and passing downwardly to a winding drum 37 adapted to be rotated thru the medium of clutch elements 38 and 39 and the shaft 40 of electric motor 41. The circuits for this 105 motor are shown in Figure 1, and will be described below. 110

In the lower position of weight 31, the gate being in elevated position, the clutch elements 38 and 39 are in engagement, having been thrown by the lever 36. When the 5 drum 37 elevates weight 31 through cable 35, and when the weight is in its upper position, the upper part of arm 36 is engaged, and clutch elements 43 and 44 are caused to engage, one of these elements being rigid with 10 shaft 45 of motor 46. A pivoted latch 48 is controlled in part by spring 49, and engages the weight, from the under side thereof, when said weight is in the position of Figures 1 and 2, so that the weight is re- 15 tained, until released by the completion of a circuit thru motor 46, the shaft of which carries a gear wheel 50 meshing with gear wheel 51 on the shaft of a drum 52 adapted to wind a cable 53, by means of which the 20 latch 48, connected with the cable, may be released from engaging position with reference to the weight. In this movement the spring 49 is compressed.

It will therefore be observed that the 25 clutches controlled by arm or lever 36 operate in reverse relation, and are engaged or disengaged according to the position of weight 31, the latter being down when the gate is up and in position for blocking or 30 obstructing the crossing.

In Figure 1, I have shown diagrammatically a track, or plurality of tracks divided into blocks designated 60, 61, 62, 63, 64, 65. The circuits for the motors 46 and 41 are 35 completed according to the position of the train with reference to the blocks. The train opens or closes the gate as the case may be, when in the end blocks, as the arrangement appears in Figure 1, and when in 40 either of blocks 61 or 64, there is no change in the position of the gate.

Assuming that the approach is from the right in Figure 1, the train entering short block 62 will complete a circuit thru wire 45 66, wire 67, motor 46, wire 68, battery 70, wire 71 and wire 72. Motor 46, acting thru the mechanism described will release latch 48, and allow the weight 31 to fall and raise the gate from the position of Figure 2 to the 50 position of Figure 3, where it constitutes a barrier. As the weight 31 moves downwardly, the cutaway portion 31' permits the end or curved part 36^a of arm 36 to move to the left, and the upper clutch is released at 43 and 44. Moreover, the downward movement of element 31 engages the lower end, or produces engagement with the 55 lower end of lever 36 and throws in clutch 38, 39. Arms 43' and 39' connect lever 36 with the clutch elements shown.

The train passing from block 62 to block 61, no further change in the position of the apparatus occurs, the gate remaining in the position of Figure 3. It may be stated incidentally, that in moving to the position of

Figure 3, the gate operated the devices of Figures 4 and 5, and raised the cover plate 20 in the manner before described. The reverse operation of the elements of Figures 4 and 5, takes place when the gate moves 70 downwardly.

When the train enters block 60, motor 41 will be energized, and the weight or counterbalance will be raised thru cable 35, so that the gate moves downwardly. When 75 element 31 reaches its upper position, it is engaged by the latch 48, as shown in Figure 2.

The circuit completed when the train, moving to the left in Figure 1 reaches block 80 60, is as follows: wire 75, wire 76, battery 70, wire 77, motor 41, wire 78, to block 60.

The circuits for the other track, and for blocks 63, 64, 65 are similar, and description thereof in detail does not seem to be necessary, it being understood that the same mechanical operation results after motors 46 and 41 are energized, in the order here named, it being assumed that the train approaches from the left in Figure 1, and that motor 46 is first energized for releasing the weight 31, so that the gate moves to the position of Figure 3, where it remains while the train is in block 64. When the train reaches block 65, motor 41 is energized, the 90 clutch, 38, 39, having been thrown in when the weight 31 descended, so that the train having cleared the crossing, cable 35 is wound, and the weight 31 is elevated, and the gate moves downwardly to inoperative 100 position.

Having thus described the invention, what is claimed is:

1. In a device of the class described, a barrier, a counterbalance therefor, electrically operated devices for raising the counterbalance, permitting the barrier to move below the level of a crossing, and electrically operated devices for releasing the counterbalance for raising the barrier when said counterbalance falls.

2. In a device of the class described, a barrier, a counterbalance therefor, electrically operated devices for raising the counterbalance, permitting the barrier to move below the level of a crossing, and electrically operated devices for releasing the counterbalance for raising the barrier when said counterbalance falls, and mechanical means controlled by the position of the counterbalance for rendering effective either of the electrically operated devices, to the exclusion of the other, in controlling the position of the barrier.

3. In a device of the class described, a barrier, a counterbalance therefor, a plurality of clutches, a lever for throwing in either clutch when the elements of the other clutch are disengaged, the counterbalance determining the position of the lever and 130

clutches, and cable winding means controlled by the respective clutches, and determining the position of the counterbalance.

4. In a device of the class described, a barrier, a counterbalance therefor, a plurality of clutches, a lever for throwing in either clutch when the elements of the other clutch are disengaged, the counterbalance determining the position of the lever and clutches, and cable winding means controlled by the respective clutches, and determining the position of the counterbalance, and electrically operated means for energizing the winding means.

5. In a device of the class described, a

barrier, a counterbalance therefor, a plurality of clutches, a lever for throwing in either clutch when the elements of the other clutch are disengaged, the counterbalance determining the position of the lever and clutches, and cable winding means controlled by the respective clutches, and determining the position of the counterbalance, electrically operated means for energizing the winding means, and a latch controlled by one element of the cable winding means, and acting to retain the counterbalance in an elevated position.

In testimony whereof I affix my signature.

WILLIAM NORRIS.
